(57) **CLAIM**

The ornamental design for a sensor and LED enclosure, substantially as shown and described.

DESCRIPTION

FIG. 1 is a perspective view of a sensor and LED enclosure; FIG. 2 is a top view thereof;

FIG. 3 is a bottom view thereof;

FIG. 4 is a front view thereof; the rear side being a mirror image; and,

FIG. 5 is a right side view thereof, the left side being a mirror image.

The broken lines are for purposes of illustration only and form no part of the claimed design.
